DESIGN FOR A ROPE ANCHOR

John A. Truhon, Detroit, Mich.

Application May 25, 1942, Serial No. 107,005

Term of patent 7 years

To all whom it may concern:

Be it known that I, John A. Truhon, a citizen of the United States, residing at Detroit, in the county of Wayne and State of Michigan, have invented a new, original, and ornamental Design for a Rope Anchor, of which the following is a specification, reference being had to the accompanying drawing, forming a part thereof, in which:

Fig. 1 is a side elevational view of a rope anchor showing my new design; and

Fig. 2 is a top plan view.

I claim:

The ornamental design for a rope anchor, substantially as shown.

JOHN A. TRUHON.
